ARTHUR P. CARTER AND MICHAEL J. HYNES, OF CHICAGO, AND JAMES C. CRONIN, OF OAK PARK, ILLINOIS, ASSIGNORS TO ARCO VACUUM CORPORATION, OF NEW YORK, N. Y., A CORPORATION OF DELAWARE

SQUEEGEE MACHINE

Application filed August 11, 1930. Serial No. 474,348.

This invention relates to machines for wiping and drying floors after the latter have been scrubbed or mopped. The machines at present available for this purpose are comparatively large and heavy and the mechanism for removing the water collected by the squeegee is of such nature that it must be driven by an electric motor, consequently such machines are expensive to install, operate and maintain.

The object of the present invention generally stated is to provide a relatively inexpensive, simple and light squeegee machine which may be actuated to remove the water from the floor by power derived from rollers running on the floor, and without entailing excessive exertion on the part of the operator.

In the accompanying drawings:

Figure 1 is a side elevation of a squeegee machine embodying the features of our invention.

Fig. 2 is a fragmental longitudinal vertical central section.

Fig. 2^a is a fragmental sectional view of the frame for the squeegee conveyor.

Fig. 2^b is a fragmental detail view showing the means for mounting the lower shaft of the conveyor.

Fig. 2^c is a detail view of a device for indicating the amount of water in the tank.

Fig. 3 is a plan view of the machine with parts broken away.

Fig. 4 is a section on line 4-4 of Fig. 2.

Fig. 5 is a section on line 5-5 of Fig. 2.

The present embodiment of the invention comprises a supporting frame composed of frame members 1, 2, 3 and 4 (Fig. 3) forming a rectangular frame, two forwardly extending bars 5 which are secured to the frame member 1, a squeegee supporting means comprising two forwardly diverging members or bars 6 which are connected together at a suitable angle, as, for example, 90°, and united at the apex of the angle, said bars 6 being secured to the bars 5, and a tie-bar 7 secured at its ends to the bars 6. The rear portion of the framework just described is supported upon two rollers 8 attached to the rear corners of the rectangular frame formed of the members 1, 2, 3 and 4.

A squeegee 9 formed of a strip of rubber is secured to the bars 6 for contact with the surface of the floor to be dried. This squeegee 9, it will be noted includes forwardly diverging members which are continuously connected at their inner portions so that in wiping over the floor, said squeegee will collect and retain in front of it the water wiped from the surface of the floor.

Means of any preferred character is provided for manually propelling the machine. The means herein shown for this purpose comprises two parallel handle-bars 10, the forward lower ends of which are pivoted to a convenient portion of the supporting framework, as, for example, at the ends of the tie-bar 7. A crossbar 11 extends between the handle-bars 10. An arm 12 pivoted to the crossbar 11 and provided with a foot 13 is adapted to serve as a prop to support the handle-bars when the latter are swung forward to give access to the tank as will appear more fully hereinafter.

The means herein shown for removing the water which is wiped from the floor by the squeegee 9 comprises a conveyor 14 arranged to elevate the water and deliver it to a tank 15. In the form herein illustrated the conveyor 14 consists of an endless belt 16 of rubber or other suitable material having transverse flights 17 of rubber which serve as squeegees to push the water up an inclined surface 18, whence the water flows through a spout 19 into the tank 15. The belt 16 is supported upon rubber-covered rollers 20 and 21 which are journaled in a rectangular frame 22 supported in an upwardly inclined position. For convenience of assembly and disassembly, the frame 22 may be made of two bars 23 the upper ends of which are bent at right angles to extend toward each other, said bent ends being detachably secured together by means of a channel bar 24. (See Figs. 1 and 2^a.) The lower end of the frame 22 is secured to the main frame adjacent to the apex of the angle formed by the bars 6. The frame 22 is supported in an inclined position by means of brackets 25 fastened to the bars 5.

The surface 18 is the bottom of a trough 100

or pan 26 secured to the frame 22, in which trough the lower run of the belt 16 travels upwardly with the squeegees 17 in contact with the surface 18. Preferably the lower run of the belt 16 is confined in proper relation to and normally held in engagement with the surface 18 by means of a backing plate 27 (Fig. 5) extending longitudinally of and across the frame 22. The spout 19 is secured to the upper end of the pan 23. A cover 28 for the upper side of the frame 22 may be secured in position in any preferred manner, as, for example, by means of screws 29. The openings through which the screws 29 extend are elongated as indicated in Fig. 1 to permit of proper longitudinal adjustment of the cover. The frame 22, pan or trough 26 and cover 25 comprise a substantially rectangular hollow casing member having the lower end thereof open and closely adjacent the surface of the floor. The lower roller 21 is located so that squeegees 17 passing around the roller 21 at the lower end of the belt 16 will project downward beyond the lower end of the pan, thereby causing the squeegees 17 to pass into the collected water and carry it up the surface 18, the lower edges of the squeegees 17 preferably but not necessarily contacting the floor surface previous to passing up the surface 18. It will be seen that the squeegees 17 at the point at which they turn to engage the body of water collected by the squeegee 9 and pass up the surface 18, are quite close to the lower edge of the latter, so that, a large part of the water engaged by the squeegee 17 is moved quickly onto and up the surface 18.

Fixed to the ends of the roller 21 are rubber-tired wheels 31 adapted to make contact with the floor when the squeegee 9 is in operative relation to the floor, as shown in Fig. 2.

As shown in Fig. 2^b the shaft 21^a of the roller 21 is supported in notches 23^a in the lower ends of the frame bars 23. When setting the machine aside after use, the shaft 21^a may be drawn down out of the notches 23^a, and released, so as to relieve the tension on the belt 16.

A lug 32 secured to the upper end of the frame 22 is adapted to be engaged by the crossbar 11 and thus serves as a rest for the handles when the latter are not in use.

The tank 15 may be of any preferred form and construction. It is herein shown as of elliptical cross-section and as being elongated to rest upon the rectangular frame formed of the members 1, 2, 3, and 4. In the upper wall of the tank is an opening 33 into which the spout 19 extends when the tank is seated upon the frame. Any desired means may be employed for removably securing the tank in place, as, for example, two curved brackets 34 pivoted to the frame member 2 and held

in engagement with the tank by means of wing nuts 35. On the upper side of the tank are handles 36. In an opening 37 in the upper wall of the tank is frictionally secured a bung 38 having a vertical opening 39 therein. A float 40 is secured to the lower end of a stem 41 which extends slidably through the opening 39. A ring or handle 42 is attached to the upper end of said stem. The elevation of the handle 42 above the bung 38 indicates the amount of water contained in the tank.

In use, after the floor has been scrubbed or mopped, the operator propels the machine over the floor, the squeegee 9 serving to wipe the floor dry. The water that collects within the angle formed by the squeegee is elevated and discharged into the tank 15 by the belt 16, the squeegees 17 of which force the water up the surface 18 and into the spout 19. The belt is driven through the rotation of the rollers 31 as the machine is pushed along the floor. After the floor has been thus dried, the small amount of water remaining in the angle between the bars 6 which cannot be picked up by the belt 16 may be removed by means of a sponge. It will be seen that the trough inclines rearwardly relative to the direction of travel of the machine, so that the lower edge of the trough moves into the body of collected water which is caused to enter the trough and be wiped up the surface 18 by the squeegees 17 together with water which is positively moved into the trough by said squeegees, the water moving up the trough in a direction counter to the direction of travel of the machine so that the inertia of the collected water acts on forward movement of the machine to aid the squeegees 17 in raising the water to the tank.

The position of the handle 42 indicates to the operator when the tank is full, whereupon the tank is removed, emptied and replaced. For convenience in gaining access to the tank 15 the handle-bars 10 may be swung forward and supported by means of the prop 12.

When it is desired to turn the machine around the operator bears down on the handle-bars 10 so as to lift the front end of the machine clear of the floor, after which the machine may be turned on the rollers 8.

As compared with devices of the prior art, the present machine is very simple and light, and inexpensive to manufacture and operate, the water-elevating mechanism being of such character that it can be actuated by the operator in the operation of propelling the machine over the floor.

We claim as our invention:

1. A squeegee machine having, in combination, a squeegee supporting means including members arranged at an angle to each other, a squeegee secured to said members and adapted to rest upon the floor, a tank located rearwardly of the squeegee, an endless belt conveyor carrying squeegees, a pan extending

- from a point near the floor within the angle formed by said members and upwardly to said tank, the squeegees on the lower run of said belt conveyor being arranged to travel 5 upwardly in said pan, a backing for the lower run of the conveyor to maintain said squeegees in wiping contact with said pan, and roller means adapted to bear upon the floor for driving said belt conveyor.
- 10 2. A machine of the character described, comprising a supporting frame, a squeegee carried by the frame and including members diverging forwardly in the direction of travel of the machine, and adapted to contact 15 a floor surface to collect water thereon and move the collected water forwardly, an inclined trough carried by the frame and having its lower end open and positioned between said members and adjacent the apex 20 of the angle formed thereby, said open end being located adjacent the floor surface, said trough inclining upwardly and rearwardly from its lower end relative to the direction of travel of the machine, an endless belt conveyor 25 extending lengthwise of the trough and having squeegees cooperable with the trough to move collected water upwardly in said trough in a direction counter to the direction of travel of the machine, means 30 to drive said conveyor, and a receptacle to receive water from the trough.
3. A machine of the character described, comprising a supporting frame, a hollow casing member secured to said frame and 35 having one end terminating adjacent a floor surface, said casing member extending upward and rearward from said end, substantially parallel upper and lower horizontal shafts supported within and adjacent the 40 ends of said casing member, an endless belt extending around said shafts within said casing member, surface engaging wheels supporting said frame and having operable connection with one of said shafts to drive said 45 belt, said casing member having its lower end open, longitudinally spaced transversely extending squeegee members carried by said belt and having cooperable wiping engagement with the lower wall of said casing member 50 whereby said squeegee members are operable to lift water from a floor surface, and a discharge aperture in the lower wall of said casing member adjacent the upper end thereof.
- 55 4. A machine of the character described, comprising a supporting frame adapted to be propelled along a floor surface to be dried, a hollow casing supported on said frame, said casing being inclined upward longitudinally 60 of the direction of travel of the frame and having its lower end open, said lower end terminating closely adjacent the surface of the floor to be dried, a container carried by said frame and having communication with the upper end portion of said casing, substantially parallel horizontal shafts within said 65
- less conveyor in said casing extending longitudinally thereof and carrying transversely extending longitudinally spaced squeegees cooperable with the bottom wall of said casing, said squeegees being operable to move liquid 70 from the floor surface upward within said casing to said container, a squeegee member supported by said frame and presenting a continuous unbroken liquid collecting wall cooperable with the floor surface, said squeegee member extending across said frame rearwardly of the lower end of said casing and projecting forward of said casing at the sides thereof whereby said squeegee member acts to dry the floor surface in the path of travel of the machine and to collect and maintain the collected liquid at the lower open end of said casing for transmission by said conveyor to said container.
5. A machine of the character described, comprising a supporting frame adapted to be propelled along a floor surface to be dried, a hollow casing supported on said frame, said casing being inclined upward longitudinally of the direction of travel of the frame and having its lower end open, said lower end terminating closely adjacent the surface of the floor to be dried, a closed container supported on said frame beneath the upper end portion of said casing and having an inlet aperture in an upper wall portion, a discharge spout depending from the bottom wall of said casing into said aperture, an endless conveyor in said casing extending longitudinally thereof and carrying transversely extending longitudinally spaced squeegees cooperable with the bottom wall of said casing, said squeegees being operable to move liquid from the floor surface upward within said casing to said spout for discharge 90 into said container, a squeegee member supported by said frame and presenting a continuous unbroken liquid collecting wall cooperable with the floor surface, said squeegee member extending across said frame rearwardly of the lower end of said casing and projecting forward of said casing at the sides thereof whereby said squeegee member acts to dry the floor surface in the path of travel of the machine and to collect and maintain the collected liquid at the lower open end of said casing for transmission by said conveyor to said container.
6. A machine of the character described, comprising a supporting frame adapted to be propelled along a floor surface to be dried, a hollow casing supported on said frame, said casing being inclined upward longitudinally of the direction of travel of the frame and having its lower end open, said lower end terminating closely adjacent the surface of the floor to be dried, a container carried by said frame and having communication with the upper end portion of said casing, substantially parallel horizontal shafts within said 100

casing and journaled in the side walls of said casing adjacent the upper and lower ends thereof, an endless belt surrounding said shafts and held under tension thereby, said belt carrying transversely extending longitudinally spaced squeegees cooperable with the bottom wall of said casing, said squeegees being operable to move liquid from the floor surface upward within said casing to said container, a squeegee member supported by said frame and presenting a continuous unbroken liquid collecting wall cooperable with the floor surface, said squeegee member extending across said frame rearwardly of the lower end of said casing and projecting forward of said casing at the sides thereof whereby said squeegee member acts to dry the floor surface in the path of travel of the machine and to collect and maintain the collected liquid at the lower open end of said casing for transmission by said belt carried squeegees to said container.

7. A machine of the character described, comprising a supporting frame adapted to be propelled along a floor surface to be dried, a hollow casing supported on said frame, said casing being inclined upward longitudinally of the direction of travel of the frame and having its lower end open, said lower end terminating closely adjacent the surface of the floor to be dried, a container carried by said frame and having communication with the upper end portion of said casing, the side walls of said casing having adjacent their lower ends alined downward open bearing slots, a shaft within said casing adjacent the upper end thereof and journaled in the side walls of said casing, a shaft having its ends extending into said slots, a resilient endless belt under tension surrounding said shafts and acting to hold said second-named shaft seated at the base of said slots, said belt carrying transversely extending longitudinally spaced squeegees cooperable with the bottom wall of said casing, said squeegees being operable to move liquid from the floor surface upward within said casing to said container, a squeegee member supported by said frame and presenting a continuous unbroken liquid collecting wall cooperable with the floor surface, said squeegee member extending across said frame rearwardly of the lower end of said casing and projecting forward of said casing at the sides thereof whereby said squeegee member acts to dry the floor surface in the path of travel of the machine and to collect and maintain the collected liquid at the lower open end of said casing for transmission by said conveyor to said container.

In testimony whereof we have hereunto affixed our signatures.
